UNITED STATES PATENT OFFICE.

THOMAS R. COOK, OF EAST CLEVELAND, OHIO, ASSIGNOR TO WILLARD STORAGE BATTERY COMPANY, OF CLEVELAND, OHIO, A CORPORATION OF WEST VIRGINIA.

DESIGN FOR A CONNECTOR FOR STORAGE BATTERIES.

54,065.

Specification for Design.

Patented Nov. 4, 1919.

Application filed December 11, 1916. Serial No. 136,376. Term of patent 7 years.

To all whom it may concern:

Be it known that I, THOMAS R. COOK, a citizen of the United States, residing at 40 Sheldon avenue, in the city of East Cleveland, county of Cuyahoga, and State of Ohio, U. S. A., have invented a new, original, and ornamental Design for a Connector for Storage Batteries, of which the following is a specification, reference being had to the accompanying drawings, forming a part thereof.

In said drawings, Figure 1 is a plan view of the connector showing my new design applied to a storage battery and conductor which are shown by dotted lines; Fig. 2 is a plan view; and Figs. 3 and 4 are edge or side views of the connector.

I claim:

The ornamental design for a connector for storage batteries substantially as shown.

THOMAS R. COOK.
